[57] CLAIM

The ornamental design for a tamper evident cap, as shown and described.

DESCRIPTION

FIG. 1 is a perspective view of the tamper evident cap showing our design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof;

FIG. 7 is a perspective view thereof with the tamper evident band removed;

FIG. 8 is a front elevational view of the embodiment of FIG. 7;

FIG. 9 is a rear elevational view of the embodiment of FIG. 7;

FIG. 10 is a top plan view of the embodiment of FIG. 7;

FIG. 11 is a bottom plan view of the embodiment of FIG. 7;

FIG. 12 is a side elevational view of the embodiment of FIG. 7;

FIG. 13 is a perspective view of the tamper evident band removed from the closure of FIG. 1 for ease of illustration;

FIG. 14 is a rear elevational view of the tamper evident band of FIG. 13; and,

FIG. 15 is a cross section view of the embodiment of FIG. 1.
